CLAIM

The ornamental design for a storage rack as shown and described.

DESCRIPTION

FIG. 1 is a front, right and top perspective view of a storage rack, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1.

FIG. 10 is an enlarged view of detail 10 in FIG. 1.

FIG. 11 is an enlarged view of detail 11 in FIG. 2; and,
FIG. 12 is an enlarged view of detail 12 in FIG. 3.

The dashed broken lines depict portions of the storage rack that form no part of the claimed design.

The dot-dash broken lines in FIGS. 1, 2, 3, 9, 10, 11 and 12 depict the boundaries of the enlargements that form no part of the claimed design.

1 Claim, 12 Drawing Sheets
